TELESCOPE OR SIMILAR ARTICLE

Heinz Kraus, Traunreut, Upper Bavaria, Germany,
assignor, by mesne assignments, to Firma Wenzler &
Heidenhain, Traunreut über Traunstein, Germany, a
corporation of Germany

Filed Aug. 14, 1962, Ser. No. 71,278

Claims priority, application Germany Apr. 25, 1962

Term of patent 14 years

(Cl. D57—1)

FIG. 1.

FIG. 2.

FIG. 4.

FIG. 3.

FIG. 5.

FIGURE 1 is a perspective side view of a telescope or similar article, showing my new design;

FIG. 2 is a perspective rear view thereof;

FIG. 3 is a front end view thereof;

FIG. 4 is a rear end view thereof; and

FIG. 5 is a top plan view thereof.

The dominant features of my new design reside in the portions shown in full lines.

I claim:

The ornamental design for a telescope or similar article, as shown and described.
